(57) **CLAIM**

I claim the ornamental design for the container and lid, as shown and described.

DESCRIPTION

FIG. 1 is a front view of the combined container, cutting board and lid;

FIG. 2 is a top view of the combined container, cutting board and lid;

FIG. 3 is a bottom view of the combined container, cutting board and lid;

FIG. 4 is a back view of the combined container, cutting board and lid;

FIG. 5 is a right side view of the combined container, cutting board and lid;

FIG. 6 is a left side view of the combined container, cutting board and lid;

FIG. 7 is a top perspective view of the combined container, cutting board and lid;

FIG. 8 is a bottom perspective view of the combined container, cutting board and lid;

FIG. 9 is an exploded view of the combined container, cutting board and lid;

FIG. 10 is a front view of the combined container, cutting board and lid, the back, left side, and right side views being identical;

FIG. 11 is a top view of the combined container, cutting board and lid, the bottom view being identical; and,

FIG. 12 is a top perspective view of the combined container, cutting board and lid.

The cutting board includes a hole as shown in phantom, with the particular shape of the hole forming no part of the invention.

The cutting board is shown separately for clarity of illustration.
